DESIGN FOR A TABLE

Max Danziger, New York, N. Y.

Application October 24, 1945, Serial No. 123,139

Term of patent 14 years

(Cl. D33—14)

To all whom it may concern:

Be it known that I, Max Danziger, a citizen of the United States and resident of New York city, in the county of New York and State of New York, have invented a new, original, and ornamental Design for a Table, of which the following is a specification, reference being had to the accompanying drawing, forming a part thereof, and of which Fig. 1 is a top plan view of a table showing my new design; and Fig. 2 is a view in side elevation thereof.

The dotted lines indicate repeat areas of circularly continuous patterns on the top and side of the table.

The characteristic features of my design reside in the portions shown by means of full lines in the drawing.

I claim:

The ornamental design for a table, substantially as shown and described.

MAX DANZIGER.
